US00D967886S

(12) **United States Design Patent** (10) **Patent No.:** **US D967,886 S**
Zhang et al. (45) **Date of Patent:** **** Oct. 25, 2022**

(54) **MONITORING CAMERA**

(71) Applicant: **HUAWEI TECHNOLOGIES CO., LTD.**, Shenzhen (CN)

(72) Inventors: **Haiyang Zhang**, Dongguan (CN); **Yanping Liu**, Dongguan (CN)

(73) Assignee: **HUAWEI TECHNOLOGIES CO., LTD.**, Shenzhen (CN)

(**) Term: **15 Years**

(21) Appl. No.: **29/764,115**

(22) Filed: **Dec. 28, 2020**

(30) **Foreign Application Priority Data**

Apr. 24, 2020 (CN) 202030174859.0

(57) **CLAIM**

The ornamental design for a monitoring camera, as shown and described.

DESCRIPTION

FIG. 1 is a front perspective view of a first embodiment of a monitoring camera, showing our new design;

FIG. 2 is a front view thereof;

FIG. 3 is a left side view thereof;

FIG. 4 is a top view thereof;

FIG. 5 is a bottom view thereof;

FIG. 6 is a front perspective view of a second embodiment of a monitoring camera, showing our new design;

FIG. 7 is a front view thereof;

FIG. 8 is a left side view thereof;

FIG. 9 is a top view thereof;

FIG. 10 is a bottom view thereof;

FIG. 11 is a front perspective view of a third embodiment of a monitoring camera, showing our new design;

FIG. 12 is a front view thereof;

FIG. 13 is a left side view thereof;

FIG. 14 is a top view thereof; and,

FIG. 15 is a bottom view thereof.
